A. KIMBLE

PULLEY VENTILATING MEANS

Filed March 6, 1922

UNITED STATES PATENT OFFICE.

AUSTIN KIMBLE, OF WAUSAU, WISCONSIN, ASSIGNOR TO MARATHON ELECTRIC MFG. CO., OF WAUSAU, WISCONSIN, A CORPORATION OF WISCONSIN.

PULLEY-VENTILATING MEANS.

Application filed March 6, 1922. Serial No. 541,550.

To all whom it may concern:

Be it known that I, AUSTIN KIMBLE, a citizen of the United States of America, and a resident of Wausau, county of Marathon, 5 and State of Wisconsin, have invented a new and useful Improvement in Pulley-Ventilating Means, of which the following is a specification.

This invention relates to belted pulleys 10 and means for ventilating same so as to avoid excessive heating especially when subjected to overload or slippage. In certain kinds of service it is desirable to provide for speed regulation and maximum load control by means of belt slippage in which case it is highly desirable to provide special or artificial means to prevent heating.

The main objects of this invention are to 20 provide improved means for cooling a pulley by artificially produced air circulation; to provide a system of motor driven belt connected machines with a common source of cooling draft for the pulleys which are subject to overload slippage; and to provide 25 in combination with a pulley having heat conductive spider or core, an extraneous source of cooling draft.

Referring to the drawings Figure 1 is a 30 conventional diagram showing a plurality of motor driven belt connected machines in plan, in combination with a blower shown in side elevation with connecting means therefor to distribute draft to the several motor pulleys.

Figure 2 is a greatly enlarged end view 35 of the slippage pulley which in this instance is mounted on the motor.

Figure 3 is an axial section on the line 3—3 of Figure 2.

Figure 4 is a slightly enlarged view of 40 one of the motors as viewed on the line 4—4 of Figure 1 and shows also the belt tension adjusting means.

Figure 5 shows a modification.

Referring to said drawings, the several 45 motor driven machines 1, which may be printing presses for instance, are driven by motors 2 respectively which are connected to the several machines by belts 3 riding on the motor pulleys 4 and machine pulleys 5.

In order to provide for ready manual adjustment of the belt tension from time to time each pulley 2 is mounted on a leverage support 6 which is provided with a horizontal

pivotal support 7 on the stationary frame 8. 55 The lever 6 is adapted to receive the motor on an upwardly projecting arm 6' and the other arm 6'' is provided with an adjusting screw 9 having threaded engagement with an upwardly projecting bracket 8' on said frame 8. A compression spring 10 is disposed between the lever arm 6'' and the threaded end of said bracket 8' and the lower end of said screw is provided with a head 9' to retain the end of lever arm 6''. 60 65

Each pulley 4 is provided with a ventilator 11, disposed in axial alinement with an air supplying nozzle 12. The several nozzles are arranged as branches of a common air conduit 13 which communicates with 70 a source of draft pressure, as for instance a blower 14.

Each pulley 4 comprises a hub 15 adapted to receive the motor shaft 16 whereon it is coturnably secured by key 16', a rim 17 and the ventilating member 11. Said member 11 is of unitary character and is preferably in the form of a brass casting and comprises a pair of concentric cylinders 18 and 19 spaced apart by a series of radially disposed longitudinally positioned web members or plates 20 adapted to present a large heat radiating surface to the ventilating draft which is discharged through said ventilator. 75 80 85

Referring to the modification shown in Fig. 5 the draft is reversed. Here the fan 21 is provided with a suction intake conduit 22 leading from the pulley 4 to the center of the fan, whereby air is drawn 90 through the pulley and into the fan.

Although but two specific embodiments of this invention are herein shown and described, it will be understood that numerous details of the construction shown may be altered or omitted without departing from the spirit of this invention as defined by the following claims. 95

I claim:

1. A power plant comprising a plurality 100 of motor driven belt connected machines arranged and adapted for slippage at the motor pulleys at predetermined loads, in combination with a source of draft pressure and distributing nozzles arranged to discharge air endwise through the several slippage pulleys. 105

2. In combination a plurality of inde-

pendently belted pulleys, each adapted and arranged to carry a belt load subject to heat generating slippage, and each adapted to admit a draft endwise therethrough in combination with a common cooling device comprising a fluid propelling means, and a system of fluid carrying conduits connected

thereto and communicating endwise with said pulleys respectively in effective relation thereto for producing a draft there-through from end to end. ¹⁰

Signed at Chicago this 27th day of February, 1922.

AUSTIN KIMBLE.
